J. HILL.
Fire-Extinguisher.

No. 224,431. Patented Feb. 10, 1880

UNITED STATES PATENT OFFICE.

JOHN HILL, OF COLUMBUS, GEORGIA.

FIRE-EXTINGUISHER.

SPECIFICATION forming part of Letters Patent No. 224,431, dated February 10, 1880.

Application filed November 7, 1879.

To all whom it may concern:

Be it known that I, JOHN HILL, of Columbus, in the county of Muscogee and State of Georgia, have invented a new and Improved 5 Apparatus for Extinguishing Fires; and I do hereby declare that the following is a full, clear, and exact description of the same, reference being had to the accompanying drawings, forming part of this specification, in 10 which—

Figure 1 is a vertical section of a building, taken through the tower, and showing the arrangement of the pipes, valves, and means for operating the same. Fig. 2 is a horizontal 15 section through the line $\alpha\alpha$ of Fig. 1. Fig. 3 is a view of the devices in the tower, looking at them from the opposite side, shown in Fig. 1. Fig. 4 is a detail of one of the valves.

My invention relates to that class of fire-extinguishers employed in large factories and in similar institutions in which a stand-pipe is connected by branch pipes and valves with a set of sprinkling-pipes in each story, whereby the water may be showered down in any 25 room or compartment in which a fire may take place.

My invention consists, mainly, in connecting the valves of each branch pipe where they join the stand-pipe and lead to the several 30 stories with a common station by means of shafts and toothed gears, and providing a handle or hand-wheel on each floor with the valve, whereby the turning on of the water from the stand-pipe to the branch pipe of any 35 one story may be effected either upon that floor or from a common station below, as hereinafter fully described.

The invention also consists in providing each shaft with spanner-connections on the 40 several floors, by which the valve of any one floor may be operated from any other floor within the building.

As an example of my invention, A A A represent the several stories of a factory, and B is a tower, having also several stories communicating through doors with the corresponding stories of the building. Within this tower is erected a stand-pipe, C, which is connected with the water-mains, a reservoir on top of the 50 building, or other suitable supply.

Extending through the upper portion of each of the stories of the building are arranged the perforated spray-pipes D D' D², each of which systems is connected with the main stand-pipe by branch pipes E E' E² through 55 their respective valves F F' F². These valves are preferably made to open by a rotary action without advancing longitudinally like a screw-valve, and they have upon one end the hand-wheels a a' a² and upon the other bevel-wheels b b' b². Meshing with these bevel-wheels are the horizontal bevel-wheels c c' c², 60 fixed to the top of independent shafts G G' G² leading to the ground floor, and stepped within a suitable metal frame, H. These shafts have 65 at their lower station, also, bevel-wheels d d' d², meshing with bevel-wheels e e' e² fixed upon the ends of short shafts f f' f², which are journaled in bearings in the frame H, and are provided with hand-wheels I I' I² for turning the 70 same. This, it will be seen, furnishes means for turning on the water into any story to the exclusion of the others, and from the ground-floor and outside of the building, where the attendant will not be subjected to the smoke and 75 flame.

If desired, the water may also be turned on at any floor without descending by means of the hand-wheels a a' a².

The upright shafts G G' G² also have couplings or rigid collars g g' g², provided with holes, into which a spanner may be fitted to turn the valve, which latter arrangement permits the valves of one story to be turned from the next or at any lower story.

In arranging the position of the hand-wheels I below I prefer to place them as to height in the order representing the respective altitudes of the stories which they control—i. e., the hand-wheel connecting with the upper story I place above the others, and so on. Where two shafts control separate sets of sprinkling-pipes on the same floor I mark the hand-wheels below with "east" or "west," "north" or "south," &c., to designate the points of the 85 building to which they lead.

When the circumstances of the case require care to prevent the freezing of the water in the pipes, the stand-pipe may be provided with a valve and waste-pipe to draw off the water 100

in the same and close it against further admission of water.

For extinguishing fires other fluid or gases may be used instead of water.

Having thus described my invention, what I claim as new is—

1. In a fire-extinguisher, the combination of a main and distributing pipes with a rotary shaft and a valve adapted to be operated from 10 a common station, or in close proximity to the valve, by means substantially as described.

2. The combination, with the water-pipes and a series of rotary shafts connecting with independent valves in the different stories, of a set of spanner-connections arranged upon 15 each shaft in each story to permit the valves of one floor to be operated from the other floors, as described.

JOHN HILL.
